UNITED STATES PATENT OFFICE.

M. ALBERT METZ, OF PHILADELPHIA, PENNSYLVANIA.

DESIGN FOR A HOOD.

SPECIFICATION forming part of Design No. 17,748, dated September 27, 1887.

Application filed May 2, 1887. Serial No. 236,884. Term of patent 3½ years.

To all whom it may concern:

Be it known that I, M. ALBERT METZ, a citizen of the United States, residing in the city and county of Philadelphia, State of Pennsylvania, have invented and produced a new and original Design for Hoods, of which the following is a specification, reference being had to the accompanying photograph.

The leading features of my design for a hood are the tufted sides of the body and the plain top thereof.

Referring to the photograph, A represents the hood, consisting of the side a, top b, bot-

tom rim, c, and ornaments d. The sides a are tufted or raised portions and the top is plain. 15 The top is sloping from front to rear.

I claim—

The design for a hood herein shown and described, consisting of the sides a, having the appearance of tufts, the plain top b, the rim c, 20 and ornament d, substantially as described.

M. ALBERT METZ.
